UNITED STATES PATENT OFFICE.

LAWRENCE SIEGER, OF CHICAGO, ILLINOIS, ASSIGNOR TO UNION BED AND SPRING COMPANY, OF CHICAGO, ILLINOIS, A CORPORATION OF ILLINOIS.

BEDSPRING.

Application filed October 15, 1924. Serial No. 743,666.

The present invention pertains to bed-springs and similar cushioning structures, its prime object being the provision or production of a construction of this character which is simple in structure, which is economical to manufacture, and which possesses particularly advantageous functional qualities, especially a high degree of resiliency and flexibility and capability of localized flexure to readily and easily accommodate itself to the contour of the body of the occupant.

To this end, in the preferred embodiment of the invention, the bed-spring has a mattress or cushion bearing portion composed of a plurality of parallel, spring-supported, flexible, metal strips or ribbons yieldingly associated together and in part supported by transverse springs equipped with clips or the like through which the metal strips or ribbons may readily slide, whereby to give to the structure that capacity for give or yield of parts to afford maximum comfort to the person occupying the spring.

To permit those skilled in this art to have a full and complete understanding of this invention, both from structural and functional standpoints, in the accompanying drawing, throughout the several views of which like reference characters have been employed to designate the same parts, I have illustrated two desirable embodiments of the invention in satisfactory commercial form.

In this drawing:

Figure 1 is a fragmentary plan view of a corner portion only of a bed-spring incorporating one embodiment of the present invention;

Figure 2 is an enlarged cross-section on line 2—2 of Figure 1;

Figure 3 is a similar cross-section of a modified construction; and

Figure 4 is a fragmentary plan view of a small portion of the structure depicted in Figure 3.

Inasmuch as both ends of the bed structure are alike, and the two side portions of the same are identical except reversed, it is merely necessary to illustrate and describe a small corner section of the bed-spring in order to give a full understanding of the structure as a whole.

The bed-spring at each end includes the usual end-bar 11 supported on brackets, not

shown, and each of the longitudinal borders of the bed-spring has a flat, marginal, metal strip 12 supported at each end by the corresponding end-bar 11 by means of a pair of coiled or helical springs 13, 13 having terminal hooks taking into holes of each.

The main portion of the mattress or cushion sustaining part of the bed-spring includes a plurality of parallel, spaced, longitudinally-disposed, metal strips, straps or bands 14, 14 preferably possessing a substantial degree of resiliency and capable of material flexure, each end of each of these bands or straps being mounted on the corresponding bed-spring end-bar by a coil contractile spring 15 having hooks at its extremities extending into apertures of the parts mentioned.

It is necessary to unite or join such strips or straps 12 and 14 together at intervals to more adequately support them and to prevent them from unduly separating or spreading apart, and, in the particular embodiment of the invention illustrated in Figures 1 and 2, this is accomplished by the employment of transverse, coiled springs 16, 16 between the bands or strips and connected together by clips 17, 17 slidably accommodating the straps or bands 14 and each supplied at its opposite ends with eyes or loops 18 for association with the ends of the corresponding springs, the terminal springs 16 of each transverse or cross row each having one end connected directly to the marginal or border member 12, this being easily accomplished by hook-ends of the springs extending down through apertures in the element 12.

It will be understood that the members 12 and 14 are not only more or less resilient in themselves, but they are yieldingly supported at their ends by the coiled springs 13 and 15 and they are crosswise associated together by the intermediate or intervening springs 16, the bands or straps being free to slide through the members joining the ends of adjacent cross springs so that the several parts of the structure may yield and come and go to give the appliance a satisfactory high degree of resiliency and comfort for the occupant.

In Figures 3 and 4 a somewhat different structure is shown, all of the parts being the same, except that each clip or band-sustaining element 17 has been replaced by a pair of wire links 21 and 22, the one above the

strap or band 14 and the other below it, as is clearly indicated in Figure 3, the two ends of each link being supplied with eyes or loops 23 through which the hook ends of the 5 coil springs 16 take to unite the parts together.

Both styles of structure are satisfactory, but the one depicted in Figures 1 and 2 has the advantage of incorporating fewer parts 10 and possibly an advantage from an economical manufacturing standpoint.

Those trained in this industry will readily understand that the invention is not limited and restricted to the particular embodiments 15 presented and many mechanical changes may be made in these without departure from the heart and essence of the invention, as defined by the appended claims, and without the sacrifice of any material advantages

accruing from the employment of the invention.

I claim:

A bed-spring composed in combination solely of end-bars, lengthwise-disposed marginal straps supported on said end-bars, 25 parallel spaced longitudinally-arranged flexible metal strips, coiled springs connecting the ends of said strips to said end-bars, and a series of parallel, straight, transverse rows of articulated members connected to 30 said marginal straps and composed of alternating coiled springs and clips rockingly connected together end to end with said clips slidingly accommodating and in part supporting said flexible metal strips.

In witness whereof I have hereunto set my hand.

LAWRENCE SIEGER.
